SECTIONAL INKING ROLLER FOR PRINTING PRESSES

Harry B. Seymour, Pearl River, N. Y.

Application October 31, 1942, Serial No. 464,010

6 Claims.

(Cl. 101—348)

This invention relates to new and useful improvements in inking rollers, and relates specifically to a sectional inking roller for lithography, gravure, and other types of printing presses.

The dominant object of my invention is to correct certain faults inherent in full length inking rollers which are fastened to one shaft and therefore have all portions of their areas rotating uniformly. In the process of printing, ink is distributed from a fountain by a series of furnishing rollers, some of which are metal and some of which are composition. The turning of each composition roller is accomplished by a metal roller which usually vibrates and which is gear driven. The composition roller, or rollers, is placed against, or set against the metal roller, or rollers thereby receiving its turning power. It is known to the pressmen that the form which the roller inks is composed of different sized pages, margins, and requires a different amount of ink in different sections because certain sections of the form require solid printing and others open printing to various degrees. Any or all of these conditions in a form causes a series of twists, slips and drags causing cutting, wrinkling, melting and general spoiling of the composition roller or rollers.

This invention particularly proposes an inking roller constructed of sections, which sections may be easily prepared to cooperate with various sections of the form requiring different amounts of ink so that each section may revolve independent of its neighboring section, avoiding strains which would cause twists, slips, cutting, wrinkling, and melting of the composition roller or rollers. It should be clear that with the sectional roller proposed by this invention the defects inherent in prior rollers will be reduced, or eliminated.

Still further the invention proposes a certain specific construction of the new inking roller which is characterized by spaced pairs of bearings having inner races releasably clamped on the shaft of the roller, and outer races with outwardly projecting radial flanges on their outer edges cooperative with a rigid tube mounted between the outer races and bearing against the flanges and supporting the inking roller composition material.

The invention proposes a modification in which the inner races are releasably clamped in such a fashion that the sections of the inking rollers may be contactively adjacent each other.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a fragmentary elevational view of an inking roller constructed in accordance with this invention.

Fig. 2 is a fragmentary enlarged sectional view taken on the line 2—2 of Fig. 1.

Fig. 3 is a fragmentary elevational view of an inking roller constructed in accordance with a modified form of this invention.

Fig. 4 is a fragmentary enlarged sectional view taken on the line 4—4 of Fig. 3.

Fig. 5 is a fragmentary enlarged elevational view looking in the direction of the line 5—5 of Fig. 3, with schematic wiring applied.

The new inking roller, in accordance with this invention, includes a rigid shaft 10. Spaced pairs of bearings have inner races 12 releasably clamped on the shaft 10. These bearings also have outer races 13 which are provided with outwardly projecting radial flanges 14 on their outer edges. A rigid tube 15 is mounted on the outer races 13, and has its ends engaging against the said flanges 14. Inking composition material 16 is mounted on the outside of the tube 15. The inner races 12 are releasably clamped on the shaft 10 by set screws 17. These set screws are threadedly engaged through projecting portions 12' from the inner races 12.

An inking roller may comprise any number of roller sections R which may be of identical lengths or different lengths, depending upon the composition of the form. The sections may easily be constructed merely by cutting the tubes 15 to required lengths. These tubes are then prepared with the composition material 16. An alternative construction would be to have long tubes with composition material and to cut these long tubes into smaller sections as required. The tubes 15 with the composition material 16 thereon are then engaged between the outer races of bearings 11. These bearings 11 may be adjusted on the shaft 10 by loosening the set screws 17 and shifting them towards or away from each other.

An important feature of the new inking roller resides in the fact that the different sections of the roller may rotate independently of each other. This eliminates stresses due to different densities of different portions of the form. The small sections of the inking roller will not be subjected to twisting, wrinkling and other destructive tendencies.

In Figs. 3—5 a modified form of the invention is disclosed which is very similar to the prior form but distinguishing in several respects. In accordance with this form, the rigid shaft 10 is provided with roller sections R which may be placed to have their adjacent ends in intimate contact with each other. Each of these sections R is constructed to embody the improvements inherent in this invention. Specifically, each

section R includes composition material 16 which is mounted on a tube 15 which is supported on the outer races 13 of bearings 11. These outer races 13 have flanges 14 which engage the edges of the tube 15.

The bearings 11 have inner races 12 which are indirectly mounted on the shaft 10. More specifically, each inner race 12 is slidably keyed on a bushing 20 which is provided with a flange portion 21 which is releasably mounted on the shaft 10 by the use of a set screw 17. Collars 22 are fixedly mounted on each bushing 20 on opposite sides to the inner race 12. Resilient means, such as expansion springs 23, are coaxially mounted upon the bushing 20 and act between the collars 22 and the sides of the inner race 12. These expansion springs 23 resiliently maintain the rollers R in fixed positions on the shaft 10.

Fig. 4 shows two of the roller sections R with their adjacent ends contacting with each other. If desired, a roller section R may be removed by gripping it and forcing it longitudinally of the shaft 10 in one direction so that the inner races 12 are forced longitudinally, exposing an end of one of the bushings 20. This exposed end will expose one of the set screws 17 which may be loosened to free the bushing from the shaft 10. Then the roller sections R may be moved longitudinally in the opposite direction to similarly expose the other set screw 17 so that the other bushing 20 may be loosened. Now the roller section is free to be shifted along on the shaft 10 and removed, as desired.

Another feature inherent in this form of the invention is the provision of means for indicating whether or not the bearings 11 are working satisfactorily in the event that there is any binding. Then rotations are transmitted to the shaft 10 and the indicator will operate. Specifically, the shaft 10 is turnably supported in the bearings 25 of the frame 26 of the printing press. The shaft 10 has a projecting end provided with a finger 27 which is cooperative with a switch 28 when the shaft 10 turns. This switch 28 is connected in an electrical circuit 29 having an audible or visible signal 30. Normally, when the roller sections R are working satisfactorily, the shaft 10 will not turn and the finger 27 will not engage the switch 28. However, when it does engage the switch, the switch is closed, which closes the circuit 29 and sets the indicator 30 into operation.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A sectional inking roller, comprising a rigid shaft, spaced bushings releasably clamped on said shaft, a bearing for each bushing having an inner race longitudinally slidably and non-rotatively mounted on said bushing and having outer races with outwardly projecting radial flanges on their outer edges, resilient means for holding said inner races centrally on said bushings, a rigid tube mounted on the outer races of said bearings

and between the flanges thereof, and inking roller composition material on the outside of each of said tubes.

5 2. A sectional inking roller comprising a rigid shaft, spaced bushings releasably clamped on said shaft, a bearing for each bushing having an inner race longitudinally slidably and non-rotatively mounted on said bushing and having outer races with outwardly projecting radial flanges on their edges, resilient means for holding said inner races centrally on said bushings, a rigid tube mounted on the outer races of said bearings and between the flanges thereof, and inking roller composition material on the outside of each of said tubes, said resilient means comprising springs.

20 3. A sectional inking roller comprising a rigid shaft, spaced bushings releasably clamped on said shaft, a bearing for each bushing having an inner race longitudinally slidably and non-rotatively mounted on said bushing and having outer races with outwardly projecting radial flanges on their outer edges, resilient means for holding said inner races centrally on said bushings, a rigid tube mounted on the outer races of said bearings and between the flanges thereof, and inking roller composition material on the outside of each of said tubes, said resilient means comprising springs about said bushing and engaging the opposite faces of said inner faces.

25 4. A sectional inking roller comprising a rigid shaft, spaced bushings releasably clamped on said shaft, a bearing for each bushing having an inner race longitudinally slidably and non-rotatively mounted on said bushing and having outer races with outwardly projecting radial flanges on their outer edges, resilient means for holding said inner races centrally on said bushings, a rigid tube mounted on the outer races of said bearings and between the flanges thereof, and inking roller composition material on the outside of each of said tubes, said resilient means comprising springs about said bushing and engaging the opposite faces of said inner faces, and acting against flanges on said bushings.

40 5. A sectional inking roller, comprising a rigid shaft, a spaced pair of bearings on said shaft having inner races and outer races, a rigid tube having inking roller composition material on its outer face mounted on the outer races of said bearings, outwardly projecting radial flanges formed on said outer races and engaging the ends of said rigid tube preventing longitudinal movement of said tube relative to said bearings, and means on said inner races locking said bearings in position on said rigid shaft.

45 6. A sectional inking roller, comprising a rigid shaft, a spaced pair of bearings on said shaft having inner races and outer races, a rigid tube having inking roller composition material on its outer face mounted on the outer races of said bearings, outwardly projecting radial flanges formed on said outer races and engaging the ends of said rigid tube preventing longitudinal movement of said tube relative to said bearings, and means on said inner races locking said bearings in position on said rigid shaft, each of said inner races having projecting portions and engaging said shaft and comprising the means for locking said bearings in position on said shaft.
